UNITED STATES PATENT OFFICE

162,601

RIBBON-RUN BEADING

Mary Ina Walden, Castle Rock, Wash.

Application October 1, 1949, Serial No. 5,252

Term of patent 14 years

(Cl. D3—32)

To all whom it may concern:

Be it known that I, Mary Ina Walden, a citizen of the United States and a resident of Castle Rock, in the county of Cowlitz, State of Washington, have invented a new, original, and ornamental Design for Ribbon-Run Beading, of which the following is a specification, reference being had to the accompanying drawings, forming a part thereof.

In the drawings:

Figure 1 is a perspective view of a ribbon-run beading, showing my new design;

Figure 2 is a plan view of one face of the beading showing the shape of the folds of the ribbon; and

Figure 3 is a plan view of the opposite face of the beading shown in Figure 2.

I claim:

The ornamental design for a ribbon-run beading, as shown and described.

MARY INA WALDEN.
